FLYER FOR SPINNING MACHINES

Henry C. Herr, Buffalo, N. Y., assignor to Herr
Manufacturing Company, Inc., Buffalo, N. Y.,
a corporation of New York

Application December 3, 1934, Serial No. 755,705

5 Claims. (Cl. 117—26.5)

This invention relates to new and useful improvements in the flyers employed in connection with spinning machines.

One of its objects is to provide a flyer of this character which is so designed and constructed as to effect a balancing of the weight as well as the centrifugal force of the flyer wire or wires, when in motion, and thereby produce an even, constant and uniform tension of the threads during the spinning operation.

10 A further object of the invention is the provision of a balanced flyer having simple and effective means for counter-balancing the weight of the flyer wires, such means being so constructed as to be readily applied to and removed from the flyer.

In the accompanying drawing:—

Figure 1 is a side elevation of a bobbin and spindle showing the improved flyer operatively associated therewith. Figure 2 is an enlarged top plan view thereof. Figure 3 is a bottom plan view of the flyer. Figure 4 is an enlarged cross section taken on line 4—4, Figure 2. Figure 5 is a detached perspective view of the balancing element of the flyer. Figure 6 is a top plan of a modification thereof.

Similar characters of reference indicate corresponding parts throughout the several views.

Referring now to the drawing, 10 indicates a spindle of the usual tapered form and 11 a bobbin mounted thereon. The flyer which is detachably mounted on the bobbin spindle may be of any appropriate construction, that shown in the drawing consisting of an anchoring sleeve 35 or journal 12 for attachment to the tapered end of the spindle, and a hub 13 rotatably mounted on the journal and carrying a wire base 14 to which the flyer wires 15 are suitably attached. By way of example, these flyer wires project from 40 one side of the hub and are retained in loops 16 formed in the base 14, a clamping ring 17 being rotatably mounted on the hub and having substantially arcuate shaped gripping faces or segments 18 thereon for securely holding or clamping 45 the wires against displacement relative to the retaining loops. As shown in Figures 1, 2, and 3, two flyer wires are shown projecting from one side of the hub, one having a depending thread-engaging eye, which, during the rotation 50 of the flyer, assumes the outwardly deflected position seen by full lines in Figure 1. The inner ends of the flyer wires are preferably bent out at an obtuse angle to be engaged by the clamping ring in the manner shown in Figure 2.

55 Projecting from that side of the flyer-hub 13

diametrically opposite to that of the flyer wires, is an element for counter-balancing the weight and centrifugal force of the flyer wires, when in motion, so that during the operation of the flyer an even and uniform tension of the threads is 5 constantly maintained. This counter-balancing element, by preference, is in the form of a wire member 19 which is substantially bail-shaped and which is so designed as to be readily applied to and removed from the wire base 14. To this end 10 the wire base has loops 20 thereon which are similar to the flyer wire-receiving loops 16, and the inner ends of the arms 21 of the bail-shaped element terminate in substantially hook-shaped portions each including an inwardly-facing 15 transverse portion 22 and an outwardly-facing 20 attaching leg 23, as shown in Figure 5. The attaching legs are adapted for engagement with the companion loops 20 on the base-plate and the bail-portions 22 abut against the inner ends of 25 the loops in the manner shown in Figure 3, while the clamping ring 13 through its corresponding gripping segment 18 is adapted to engage the opposing sides of the bail-portions 22 to thereby 30 effectually clamp the counter-balancing bail to 25 the base plate. In applying and removing the bail to and from the base plate, the clamping ring is turned to the position shown in Figure 3, whereby the bail is free to assume the position shown by dotted lines in said figure to permit its 35 ready removal from the base plate or to permit its legs 23 to be threaded into engagement with the loops 20.

By mounting the counter-balancing element 19 in this manner, it can be readily applied to and 35 removed from the base plate, and they can be made in different weights of wire corresponding to the weights of wire used on corresponding flyer wires, so as to properly balance the flyer. Furthermore, the clamping means which serves to 40 anchor the flyer wires 15 in place also serves to detachably hold the counter-balancing element to the flyer, thereby providing on the whole a balanced flyer which is manifestly simple and inexpensive in construction and which affords ready 45 renewal and replacement of both the flyer wires and the balancing wire.

In the modified form of the balancing element shown in Figure 6, the bail 24 terminates in outwardly-bent hook-shaped portions or legs 25 50 with the shanks 26 in adjoining relation and adapted for disposition between the returning loops 20 of the flyer base 14.

I claim as my invention:—

1. A flyer, comprising a body having a flyer wire 55

projecting from one side thereof and an attaching loop in its opposite side, and an element for counter-balancing the weight of the flyer wire projecting from such opposite side of the body, said counter-balancing element being shaped from wire and having its inner end shaped to provide an outwardly-facing attaching leg engaging said loop.

2. A flyer, comprising a body having a flyer wire projecting from one side thereof and a retaining loop in its opposite side, and a bail-like wire element for counter-balancing the weight of the flyer wire projecting from such opposite side of the body and having a substantially hook-shaped inner end including an outwardly-facing attaching leg detachably engaging said loop.

3. A flyer, comprising a body having a flyer wire projecting from one side thereof and a retaining loop in its opposite side, means on said body for clamping the flyer wire thereto, and a bail-like wire element for counter-balancing the weight of the flyer wire projecting from such opposite side of the body and having an attaching leg engaging said loop and a portion disposed for engagement

with the flyer wire clamping means, the latter holding the bail-like wire against displacement from its retaining loop.

4. A flyer, comprising a body having retaining loops on its diametrically opposite sides, a flyer wire projecting from one side of said body and engaging the companion retaining loop, a wire element projecting from the opposite side of said body to counter-balance the weight of the flyer wire and having an outwardly-bent portion at its inner end to provide an attaching leg extending outwardly through the corresponding retaining loop, and a rotatable clamping ring arranged substantially centrally of the body for interlocking engagement with said flyer wire and said counter-balancing wire element.

5. The combination with a flyer body having adjoining retaining loops thereon, of a wire bail-like element detachably mounted thereon and having its side arms terminating at the inner end in substantially hook-shaped portions including outwardly-facing attaching legs adapted to engage said loops.

HENRY C. HERR.
